SWITCH STAND

Walter S. Newhall, Chagrin Falls, Ohio

Application May 13, 1935, Serial No. 21,150

11 Claims. (Cl. 246—405)

This invention relates to a railway switch stand of the type employing a horizontal spiral cam coacting with a longitudinally shiftable bar connected to the switch points, a half rotation 5 of such cam throwing the switch from one position to the other. Mechanism between the cam and the banner mast, which carries the signal or lamp, automatically turns such mast 90° for each throw of the switch. Such type of switch stand, being located adjacent the ground, is susceptible to damage, as by reason of some object falling off a passing train or projecting from said train or by being struck by a moving body or vehicle at a highway crossing.

15 It is an object of my invention to so devise a switch stand of this type that it shall be as little as possible subjected to dangers of external injury or obstruction. In my switch stand, the entire mechanism both for operating the slide bar 20 and for turning the banner mast is entirely protected by the frame of the stand. At the same time I have been able to reduce the size of the frame and make it more compact, rendering it less liable to breakage, while reducing the expense of construction.

Another object of my invention is to so devise the stand that may be readily converted from a right-hand to a left-hand stand, using the same frame and most of the operating parts, a left-30 hand spiral cam being substituted for the right-hand. This enables the switch stand to take care of switches extending in either direction from the track and still enables the switch operating lever to be located as desired and the slide bar 35 on its connection with the switch points maintained in tension to keep a snug connection between the active switch point and the adjacent rail.

The particular characteristics of my switch stand by which I accomplish the objects above referred to will be more apparent from the following detailed description of a preferred embodiment illustrated in the drawings.

In the drawings, Fig. 1 is a plan of the switch 45 stand complete; Fig. 2 is an end view thereof; Figs. 3 and 4 are horizontal sections through the switch stand in broken planes substantially as indicated by the lines 3—3 and 4—4 on Fig. 5; Fig. 5 is a vertical cross-section through the center of the stand; Figs. 6 and 7 are views of the operating cam when the spiral groove extends in the direction for a so-called right-hand switch stand; Fig. 8 is a view similar to Fig. 7 but shows a cam for a left-hand stand; Fig. 9 is a plan of 50 a modified form of stand intended for use with

a comparatively tall banner mast; Fig. 10 is a sectional end elevation of the stand shown in Fig. 9; Fig. 11 is a diagram illustrating a track layout, embodying my right and left-hand switch stands.

As shown in Figs. 1 to 5 inclusive, the frame of the switch stand comprises primarily a single integral casting 10 having an approximately cylindrical barrel 11 and laterally extending wing portions 12 and 13 forming a base. On each side 10 of the base frame 12 has an inclined portion 14 connecting it with an intermediate region of the barrel and on each side identical provision is made for carrying the banner mast as hereinafter explained. The two base portions 12 and 13 are 15 flat on their undersides and adapted to rest on two ties between which the slide bar 50 operates.

As is customary in switch stands of this type, the barrel is closed by an end plate 20, held in place by bolts 21 mounted in cavities in the main casting and projecting therefrom and nuts screwing on the bolts. Mounted within the barrel 10 is a spiral cam 30 which is cast about a shaft 32 journaled in the plate 20 and in the main casting and having at its end an angular portion 33 to which is secured an operating lever 40. Slidably mounted in the main casting beneath the cam 30 is a slide bar 50 carrying a roller 51 occupying the groove 35 of the cam. Accordingly, the movement of the operating lever from its position as shown in Fig. 1 through 180° to the opposite position gives the cam a half rotation and moves the slide bar 50 from one extreme position to the other to throw the switch. The spiral groove 35 of the cam terminates in portions which are at right angles to the axis and are closed at their end by the wall 36 of the cam, illustrated in Fig. 6, thus forming a positive stop and lock for the extreme positions of the slide bar and preventing any stress applied to the switch points 40 from shifting the bar.

The barrel portion 11 of my frame is cylindrical for the major portion and closely houses the cam 30, as illustrated in Fig. 5. At the lower portion of the cylindrical cavity there is a 45 channel shaped portion having substantially vertical walls 15 and a bottom web 16. On the inner faces of these walls are ledges 17 on which slidably rest the flat slide bar 50. This makes an effective support and guide for the slide bar and a clearance space for dirt beneath it. This clearance space is opened by an orifice 58 through the base web 16.

The cam engaging roller 51 is rotatably mounted on a stud 52 carried by the slide bar 50. The 55

stud is shown as passing through the slide bar and is shown as peened over on its lower end but may be attached in other manner.

Since my switch stand is convertible for right or left-hand operation, I make provision for mounting the banner mast on either side of the cam housing and in either case connect it with the slide bar. To this end I form on each side of the frame a hollow vertical boss 70 and below that an inwardly projecting horizontal web 71. The web and boss have aligned bearing openings as shown. The mast 60 is shown in Fig. 5 as having a reduced portion 61 journalled in the openings of the boss and web at the left-hand of the cam housing, while the opening in the boss at the right-hand is closed by a suitable plug cap 65. In case of the left-hand switch stand, the banner mast and plug cap would be interchanged.

To give the mast a quarter-turn consequent upon a half rotation of the cam, I secure a crank arm 80 rigidly to the lower end of the mast and I connect this arm with a bar 90 which is tightly secured to the slide bar. As shown, the crank 80 embraces a squared portion 67 of the mast and is rigidly held in place by the peened-over lower end of the mast though the attachment may be in any other manner desired. This crank carries a roller 83 mounted on a crank pin 84 which is preferably integral with the crank and is peened over at its lower end to hold the roller in place. The roller occupies a slot 91 in the transverse bar 90.

The bar 90 is rigidly connected to the slide bar as shown; the bar 90 rests on top of the slide bar and has a downwardly projecting rib 92 engaging the edge of the slide bar and the two bars are rigidly held together by the roller pin 52. This pin has a shoulder engaging the upper end of the lateral bar 90 and when the lower end of the pin is secured the lateral bar is tightly held to the slide bar.

The bar 90 extends from the slide bar at right angles thereto through a horizontal slot 95 formed in the main casting 10. This slot is of sufficient height to readily accommodate the lateral bar as shown in Fig. 5. Identical slots are formed in the opposite walls of the slide bar housing so that the lateral bar may extend in either direction through one slot or the other as desired. The portion of the switch stand frame beneath the slots is thoroughly braced by the webs 19 of the housing which extend beneath such lower portion.

It will be seen that the cam and roller are entirely housed within the barrel of the frame and that the adjacent channel of the frame provides an effective guide and protection for the slide bar and part of the banner operating bar 90. This latter bar extends from the slide bar outside of the housing for the cam and switch bar, but it will be noticed that it is directly beneath the side frame 14 of the main frame and protected thereby. This protection applies also to the crank 80. The result is that without enlarging the housing for the cam I have so arranged the connecting mechanism to the banner mast that it cannot be struck by anything dropped from a passing train or obstructed by snow or ice.

As the frame portion 13 rests on and is secured to a tie, a portion of the crank 80 may be over such tie. The rest of the crank and the projecting portion of the bar 90 beyond the cam housing is, in effect, housed between the end webs 19 of the frame adjacent the tie. Accordingly, when the switch stand is mounted not only are the cam and roller for the slide bar entirely housed within

the frame, but the banner operating mechanism is also in effect housed. Nevertheless, I accomplish this without having to provide a large hollow casting enclosing the cam and entire operative mechanism.

As heretofore stated, Fig. 5 illustrates the switch stand as a right-hand stand, the cam being of the form shown in Fig. 7. In case of a left-hand stand, the frame is identical but the cam would be of the form shown in Fig. 8. The lateral bar 10 90 would extend through the right-hand slot in the slide bar housing; the mast would occupy the right-hand boss 70 and its crank would connect with the lateral bar extending in that direction. I prefer to make up the complete switch stand either 15 as a right-hand stand or left-hand stand in the shop and peen over the lower ends of the cam roller pin and the mast to make permanent connections. However, if desired, the pin and mast may simply extend below the slide bar and crank 20 respectively and receive cotter pins or other fastening means, and in that case the change from right to left-hand stand may be readily effected in the field.

In assembling the parts, the slide bar 59 may 25 be put in place, the banner operating bar 90 passed through the slot, and the pin 52 installed through the bar 90 and the slide bar. Then the lower end of the pin may be peened over by means of a suitable tool passed through the opening 58 in 30 the base plate 16, the pin at such time being held in registration with the opening, or a cotter pin installed, if that type of fastener is employed. The crank 80 carrying the roller 83 may be readily 35 installed by placing the roller in the slot of the bar 90 and mounting the crank on the mast 60 and peening over the lower end of such mast, which is accessible on the underside of the frame, or applying cotter pins thereto. The roller 51 is then placed on the pin 52, and the cam may be 40 passed into the open barrel 11 so that its slot embraces the roller 51 and the shaft 32 passes to the outside through the hub at the end of the barrel. Then the cap plate 20 may be mounted at the other end of the cam, and finally the operating lever 40 mounted on and secured to the 45 square end 33 of the shaft.

In Figs. 9 and 10, I have illustrated a modified form of switch stand frame designed particularly for accommodating masts of considerable height. 50 In this case the housing for the cam and slide bar is identical with that heretofore described but on each side of the cam housing I make hollow bosses 72 of considerably greater diameter than the bosses 70 of Fig. 5 and at the top of 55 these bosses 72 I provide a nearly annular flange 73. Mounted on one of the flanges 73 is a tubular standard 75 terminating at its upper end in a flange 76. Mounted on the flange 73 at the other side of the cam barrel is the foot of the 60 diagonal brace 77 which has at its upper end a flange head 78 mating with the flange 76.

Fig. 10 shows the parts described with the standard at the left-hand side of the barrel and the brace secured at the right-hand side and 65 overlapping the top of the standard, all parts being secured by removable bolts. In the case of a left-hand switch stand, the standard 75 and the brace 77 are interchanged so that the mast will stand at the right-hand side of the barrel in 70 Fig. 10, and the brace be secured to the left-hand side. In either case the mast designated 60 has a reduced lower extension journalled in the top plate of the boss 72 and in the internal web 74 beneath it. The connection of the mast to the 75

slide bar is identical with that heretofore described, that is to say, by means of a crank 89 on the lower end of the mast having its roller occupying the bar 90 and secured to the slide bar 50.

The standard and diagonal brace form an effective support for a comparatively tall mast. The brace bar rigidly holds the upper end of the standard which provides the upper bearing for the mast. The extreme horizontal end of this brace bar may be formed into a step 99 on which the attendant may readily stand when placing the lamp on the mast. By employing switch stands of the right and left-hand type, the mast 10 may always be on the far side of the stand with reference to any highway crossing, and hence the brace bar will incline in the direction from the highway crossing toward the mast, and thus will 15 serve as a shield and deflector for the switch stand proper.

In the diagram Fig. 11, I have indicated at 100 and 101 a pair of main tracks for use in the direction indicated by arrows. 102 indicates a cross-over switch connecting these tracks extending in the direction to make the switches 103 and 104 both trailing point switches, as desired. The slide bars of the switch stands S1 and S2 are maintained normally in tension by reason of employing the left-hand and right-hand type of switch stand respectively.

In the diagram, 105 and 106 indicate cross-overs from the two main lines to the sidings 107 and 108. These cross-overs also present trailing point switches to the main lines. They are controlled by the switch stands S3, S4, S5 and S6, which are of either right or left-hand type, as indicated in the diagram by the letters RH or LH. Finally, the diagram illustrates at 109 various turn-out switches from the two sidings, shown as 20 controlled by the switch stands S7, S8, S9 and S10. These switch stands also are of the right and left-hand type, as indicated.

It will be seen from the diagram that by employing right and left-hand type of switch stands, 25 I am enabled in every case to maintain the switch points tight against the rail normally engaged, the slide bar being under tension and controlled by the operating lever 40 extending always normally away from the highway crossing. It will 30 be noticed also that in each case the banner and banner mast indicated at 60 are on the distant side of the switch stand frame 10 from such highway crossing.

It will be seen that my construction in either 35 form illustrated is simple; that the operating mechanism is direct and effective, and the frame so designed as to house the cam and roller, and thoroughly protect all the other moving parts without undue size or weight, and that the change 40 from right to left-hand stand may be readily effected as desired.

By employing such right and left-hand stands, I meet any condition arising in practice, requiring 45 switches between main tracks and passing sidings or between other tracks, and am enabled to have the mast always on the far side of the switch stand with reference to any highway crossing, so that in case of injury to the mast its distortion will not disturb the operating mechanism of the 50 switch stand. Also, as the operating lever may always normally project away from such crossing, it is less liable to be displaced by obstructions encountered at the crossing.

I claim:

1. In a switch stand of the class described, the

combination with a slide bar, a cam connected therewith for operating the slide bar, and a banner mast, of a frame having a housing enclosing both the cam and its connection to the slide bar, said frame having an extension adapted to rest 5 on a tie and support the housing while providing a space beneath the extension and over the tie, and operating mechanism for the banner mast connected with the slide-bar and located in part within said housing and part outside of the housing, the latter part lying in the said space beneath the extension, whereby the extension guards said latter part from above and the tie guards it from beneath.

2. In a switch stand of the class described, the 10 combination with a slide bar, a cam for operating it, and a banner mast, of a frame having a barrel substantially enclosing the cam and its connection to the slide bar, and having an extension adapted to rest on a tie and furnish a support for the 15 barrel, said extension having a cavity on its underside substantially closed by such tie, a crank on the banner mast lying in the cavity of said extension, normally over such tie, a lateral opening 20 in the wall of the barrel, and an operating member secured to the slide bar and extending from the interior of the barrel through said opening to the crank.

3. In a switch stand of the class described, the 25 combination of a barrel, side wings rigidly connected therewith and adapted to rest on railway ties in a manner to support the barrel, one of said wings having a recess on its underside at least partially closed by the tie on which it rests, a 30 banner mast externally of the barrel, a cam within the barrel, a slide bar extending into the barrel and operatively connected with the cam, and mechanism between the slide bar and banner mast, said mechanism including an operating part 35 extending from the bar through an opening in the barrel wall, and a cooperating part connected with the mast, one of said parts occupying a portion of said recess which is closed from below by such tie.

4. In a switch stand of the character described, 40 the combination of a frame comprising a hollow barrel, lateral supports therefor adapted to rest on railway ties, one of said supports having a recess on its under-side bounded by downwardly 45 extending flanges at the opposite ends and one 50 side of the recess, said recess being closed from below by the tie on which the recessed support is adapted to rest, a slide bar extending into the frame, a cam in the frame engaging cooperating means on the slide bar, a banner shaft mounted 55 on the frame and extending into the recess, a crank on the banner shaft located in the recess, and a lateral bar connected to the slide bar extending through a slot in the frame toward said 60 recess and operatively connected with the crank.

5. A switch stand comprising a housing, a spiral cam in the housing, a slide bar adapted to be coupled with a switch point and operatively connected with the cam, extensions on opposite sides of the housing, adapted to rest on railroad ties 65 and to support the housing, means carried by each extension for interchangeably supporting a banner mast, and an interchangeable connection between said mast and the switch operating mechanism.

6. In a railroad switch stand comprising a hollow housing containing operating mechanism for a switch and a banner mast, the housing having side wings thereon for resting on adjacent ties to support the housing, the combination of a tubular 70 75

standard on one of the wings arranged to support such mast, and a brace bar having one end rigidly secured to the other wing and the other end rigidly connected to the top of the standard.

- 5 7. In a railroad switch stand having a housing containing operating mechanism for a switch and a banner mast, wings on the housing, a standard adapted to support such mast and interchangeably attachable to either wing in a manner to associate the mast with its operating mechanism in either position, and a diagonal brace bar for the standard interchangeably connectible with whichever wing is unoccupied by the standard.
- 10 8. In a switch stand, the combination of a housing having a barrel-like portion and a trough-like portion beneath it, supporting wings on opposite sides thereof, a spiral cam in the barrel-like portion, a slide bar extending into the trough-like portion, means on the slide bar engaged by the cam, whereby the cam may operate the slide bar, journals for a banner mast carried by the frame on the opposite sides of the barrel portion of the housing, slots through the side walls of the slide bar trough, a lateral bar adapted to be secured 20 to the slide bar and to extend through either of said slots, and a crank secured to the banner mast in either of said journals and connected to the lateral bar.
- 25 9. In a switch stand, the combination of a frame comprising a barrel-like housing with a trough-shaped housing beneath it and lateral supporting wings, slots through the walls of the trough-like portion adjacent the junction of the barrel-like portion, webs connected to the wings and the barrel-like portion of the frame and extending beneath the trough-like portion to brace the same, means for journaling a banner mast

on the frame on either side of the barrel portion, a cam in the barrel portion, a slide bar in the trough-like portion, a lateral bar extending from the side bar through one of said slots, and a crank on the lower end of the banner mast connected to the lateral bar.

10 10. In a switch stand, the combination of a frame having a housing and supporting wings on opposite sides thereof, a pair of vertical bosses with external flanges respectively on opposite sides of the housing, a standard having a bottom flange, a brace bar having a bottom flange, said standard and brace bar being interchangeably connected with the respective flanges on the frame at their lower ends, the brace bar and standard being adapted to be connected together at their upper ends, an operating cam and an operated slide bar in the housing, and a connection between the same and a banner mast mounted in the standard.

15 11. In a switch stand, the combination of a frame having a barrel-like housing with a trough-like housing below it and including wings on opposite sides of said housings, an operating cam in the barrel-like housing, an operated slide bar associated with the cam, a pair of hollow vertical bosses forming part of the frame on opposite sides of the barrel-like housing, a tubular standard secured at its lower end to one of said bosses, a brace secured at its lower end to the other of said 25 bosses, said standard having an external flange at its upper end and the brace having a head extending over and secured to the flange, and a banner mast mounted in the tubular standard and operatively connected with the slide bar and 30 cam.

WALTER S. NEWHALL.
